UNITED STATES PATENT OFFICE.

JOHN C. CHAPMAN, OF CHARLESTOWN, MASSACHUSETTS.

IMPROVEMENT IN MACHINES FOR DRAWING BOLTS AND SPIKES.

Specification forming part of Letters Patent No. 37,332, dated January 6, 1863.

To all whom it may concern:

Be it known that I, JOHN C. CHAPMAN, of Charlestown, in the county of Middlesex and State of Massachusetts, have invented an Improved Machine for Drawing Bolts and Spikes from Timbers, &c., of which the following is a full, clear, and exact description, reference being had to the accompanying drawing, making part of this specification, in which is represented a central longitudinal section through my improved machine.

My invention has for its object to remove bolts or spikes from timbers or sides of ships, &c., while undergoing repairs more economically and expeditiously than is accomplished by the machines for that purpose now in use, and, as it is desirable to use the withdrawn bolt again, I construct my machine so that it may be drawn without injury or bending.

My said invention consists of a pair of levers linked together, the upper ends of which slide in inclined grooves in the foot of a screw-shaft, their lower ends forming jaws or nippers, which grip and draw the bolt outward as the shaft ascends.

To enable others skilled in the art to understand my invention, I will proceed to describe the manner in which I have carried it out.

In the drawing, A is a metal frame, of sufficient strength to bear the required strain, the lower part of which rests upon the face of the timber from which the bolt is to be drawn. Through a hole in the top of this frame passes the shaft B, having a screw-thread cut upon its entire length, and on which works a nut, C, turned by handles a, thus raising or lowering the shaft B. This shaft is made hollow for the purpose of receiving the end of a bolt, which might project some distance from the face of the timber. The lower end of the shaft B terminates in a circular foot-piece, D,

in the periphery of which and diametrically opposite to each other are cut two inclined grooves, b b. Within these grooves slide the upper ends of two levers, E E, pivoted or shackled to the links c. The lower ends of these levers (which are of hardened steel) form jaws or nippers, which are provided with asperities on their inner surfaces, so as to clutch firmly the bolt to be drawn. The backs of these levers slide in slotted guides d d in the uprights of the frame A A, and are thus kept in a position for insuring a proper hold of the bolt.

The operation of drawing the bolt is as follows, viz: The machine is placed over the bolt to be drawn. The part of the bolt projecting above the timber is embraced by the jaws, and the operator, turning the handles a a of the nut C, raises the shaft B and foot-piece D. As the foot-piece is raised, the upper ends of the levers sliding in its grooves are forced farther apart and cause the jaws or lower ends of the levers to take a firm hold of the bolt, and grip it with such force as to withdraw it from the most tenacious timber and without bending or otherwise injuring it. It is evident that the greater the resistance to the withdrawal of the bolt the greater will be the force with which the jaws are made to grip it.

What I claim as my invention, and desire to secure by Letters Patent, is—

The within-described machine for drawing bolts, consisting of the combination of the frame A, the screw-shaft B, with its foot-piece D, and the jaws E, arranged and operating as set forth.

JOHN C. CHAPMAN.
